UNITED STATES PATENT OFFICE.

EDWARD B. ROBY, OF TROY, NEW YORK, ASSIGNOR TO STANLEY M. STONE, OF COHOES, NEW YORK.

FOLDING MACHINE.

Substitute for application Serial No. 179,853, filed July 11, 1917. This application filed May 26, 1923.
Serial No. 642,723.

This invention relates to folding machines of the character adapted to fold, or turn the edge parts of moistened fabric blanks over and around a die-plate, of any suitable contour, and heating and pressing said blanks; the objects of the invention being to provide means whereby the blanks are rapidly prepared for delivery to sewing machines, and to conserve time and labor in the process of manufacturing collars, cuffs or analogous articles requiring turned edges.

Folding machines of the character named comprise inwardly slidable folders, a downwardly and upwardly movable cross-head and die-plate, a heated upwardly and downwardly movable bed-plate and means for operating said parts. This application is a substitute for my abandoned application Serial No. 179,853 filed July 11, 1917 for "folding machine."

In carrying out my invention, I employ novel parts and operating means therefor which are simple and durable in construction, automatically operable, and assembled corelatively in such manner, that a minimum of motive force and initial manual labor is required for their successful subsequent automatic operation, all as hereinafter full described and specifically set forth in the annexed claims.

In the accompanying drawings forming part of this specification, Figure 1 is a front view, partly in vertical section, of my improved folding machine. Fig. 2 is an end view of the upper part of the machine. Fig. 3 is a plan view. Fig. 4 is a cross sectional elevation taken on the line 4—4 of Fig. 3. Fig. 5 is a detail vertical sectional view, drawn on an enlarged scale, showing the means for operating the folders. Fig. 6 is a detail cross sectional view taken on the line 6—6 of Fig. 4. Fig. 7 is a detail sectional plan view taken on the line 7—7 of Fig. 1. Fig. 8 is a vertical section taken on the line 8—8, of Fig. 7. Fig. 9 is a vertical section taken on the line 9—9 of Fig. 8.

In the example of my invention illustrated by the accompanying drawings A, represents a frame-work of adaptable design and construction for supporting the several parts comprising my invention, and having through its top plate *a*, an opening for accommodating an upwardly and downwardly

movable bed-plate *B*, which is heated by means of an insulated high resistance conductor *b*, which is in electrical connection with a source of supply *X*.

Fixed on a vertical central line beneath the top plate *a*, is a cylinder *C*, for the accommodation of a reciprocating piston *D*, having a piston rod *d*, which passes through the head *c*, of the cylinder *C*, and is fixed to a supplemental rod or extension *e*. Said extension *e*, is in connection with a reciprocating piston *E*, located within an oil-containing cylinder *F*, secured to the frame-work *A*, and located in vertical central alignment beneath the cylinder *C*, the oil in the cylinder *F*, acting as a cushion to prevent jarring or pounding of the piston *D*.

Resting on a spiral spring *f*, supported by means of a laterally extended collar *G*, and adjustably secured to the rod *e*, is a yoke *H*, having upwardly extended arms *h*, which are respectively provided with a shoulder or stop *i*, for engagement beneath the head *c*, of the cylinder *C*, to limit the upward stroke of the said yoke. This yoke is adapted for operating the bed-plate *B*, by means of rocking levers *I*, which are fulcrumed on pins *1*, of extensions *2*, of the frame-work *A*, and connecting bolts *J*, extended upwardly from opposite ends of the yoke *H*. Each rocking lever *I*, is provided with a bifurcated end part *j*, having laterally extended therethrough a rotatable pin *k*, having a screw-threaded opening leading therethrough, and each bolt *J*, is provided with a screw-threaded upper end part which is in threaded engagement with its respective pin *k*. The levers *I*, at their outer ends are each provided with a roller bearing *3*. The bed *B*, is directly supported by means of plate springs *4*, extended outwardly from the levers *I*, and adjustably fixed by means of set screws *5*.

Pivottally secured between integral extensions *m*, of the cylinder head *c*, is a lever *K*, having a downwardly and inwardly extended bifurcated end part carrying a revoluble roller *n*, which bears within a cam-like recess *6*, formed in the piston rod *d*. The lever *K*, also has a bifurcated outer end through which is extended a pin *7*, engaging a slot *8* of a link *L*. Said lever *K*, is also provided with a roller *9*, for engage-

- ment with a curved presser bar hereinafter described. Said lever K is normally held in position shown in Fig. 4, of the drawings by means of a spiral spring 10, which is secured 5 at its upper end part to an eye 11, of the lever K, and at its lower end to an eye 12, fixed to the lower part of the frame-work A. Located diametrically opposite the lever K, and in pivotal engagement between extensions m' , for the cylinder head c , is a similar lever M, carrying at its inner end a roller p , for engaging a recess g , of the rod d , and at its outer end a link N, which is pivoted to a pin 14. Said lever M, is held 10 in normal position shown in Fig. 4 of the drawings, by means of a spiral spring 15, secured at one end to an eye 16, of the lever M, and at the other end to an eye 17, fixed to the frame-work A.
- 20 The links L and N, are each provided with an upwardly extended part O, having slots q , for engagement with pins r , of levers R, which are pivoted to depending extensions S, of the top plate a , of the frame-work A. These levers are respectively provided with a bifurcated outer end part s , and they engage sleeves T, for operating folder-plates hereinafter described.
- 30 The said sleeves T, respectively engage a reciprocating rod U, which slidably bears in a bushing, or cylindrical casing V, adjustably and rotatably mounted in and extended through the top plate a , of the frame-work A. These bushings each have a flange, or 35 extension v , having a groove therein which engages a tongue w , of a slide W.
- 40 Each rod U, is provided at its upper end with an angularly extended part u , which passes through an angularly extended opening of its connected slide W, whereby downward movement of the rod U, causes the slide to move inwardly on a horizontal plane and upward movement again carries the slide back to its initial position. The rods 45 U, are further respectively provided with an adjustable stop y , at the lower end.
- 50 The bushings V, extend through hubs a' , of the plate a , and they may be rotated therein for the purpose of setting the slides 55 at a required angle, and held in fixed position by means of the collars 18 and set screws 19.
- 55 Each slide W, is provided with a cylindrical boss 20, and said bosses are extended through spiders 21, which are in adjustable connection with folder plates 22, said plates are connected in pairs by means of parallel bars 23 and links 24, whereby they are allowed independent movement.
- 60 Adjustably fastened to the folder plates 22, by means of bolts 25, which pass through slots 26, are overlapping infolder-plates composed of thin sheet metal and of any required contour, as 27, 28, 29 and 30.
- 65 Rotatably supported on a shaft 31, ex-

tended between bearings 32, of the plate a is a curved presser arm 33, having a bifurcated and arched extension 34, carrying a set screw 35, and a downwardly extended curved arm 36, having a shoe 37, for engagement with the roller 9, hereinbefore described. Also swinging on the shaft 31, is a four-armed and curved hanger 38, which carries the cross-head 39 and the die-plate 40, over which the blanks are turned. 70 75

In rotatable, or swinging engagement with the shaft 31, is a lever 41, which is in pivotal engagement with a connecting rod 42, which engages a treadle bar 43. Said bar is pivoted to a fixed bearing 44, and has a 80 swinging treadle on the forward end thereof.

The presser arm 33, and its connected parts are normally held in position shown by dotted lines Fig. 4 of the drawings, and it is 85 in flexible connection with the hanger 38, by means of a spring 45, and the connecting bolt 46 and nut 47.

Adjustable and swinging presser fingers 48, are employed for holding down the 90 plates 22, at their side parts, and double presser fingers 49, are employed at each end, the spiders 21, being recessed for the accommodation of the knobbed end parts of 95 said presser fingers. Said parts being held together by means of straps 50, whereby the spiders 21 and all their connected parts may be simultaneously removed from the machine in compact and attached relative arrangement when it is desired to substitute 100 different shaped dies and folder plates.

The cylinder C, communicates with a valve box 51 by means of a port 52, which leads into the valve chamber 53, housing the sliding valve 54, which is connected to a 105 valve stem 55. Said stem is adjustably connected to a connecting rod 56, which is provided with a collar, or stop 57, and it is pivoted at its lower end to the treadle bar 43; and a spring 58 is employed to normally maintain the valve 54, in closed position illustrated by Fig. 8 of the drawings.

The compressed air for operating the piston D, is admitted through the pipe 59, and exhausted through the pipe 60. 110 115

In the operation and use of the invention, downward movement of the pedal into position shown by full lines Fig. 4 of the drawings, operates the presser arm 33 and its connected parts by means of the rod 42, carrying the die and head downwardly into position shown by full lines Fig. 4. This movement also operates the valve 54, opening the port 52, allowing access of compressed air to the cylinder C, over the piston 120 D, and at the same time closing the exhaust. The downward movement of the piston D and its recessed rod d , swings the lever K, upwardly until its roller 9, engages the shoe 37, to hold the head 39 and its connected die 125 130

40, down while the folders are being operated. Thus when a blank is placed upon the bed B, the first action is to press and hold it in position. Further movement of the piston D operates the back levers R, through the medium of the link L, its slot 8, allowing the lever K, to move sufficiently to allow its roller 9, to engage the shoe 37, before the levers R, start their movement. 15 These back levers R, carry the sleeves T, downwardly until they contact with their respective stops y, further movement of the levers causing the rods U, to move their connected slides W, and folder plates 27 and 28, 20 over the die, whereby the edges of the blank are turned. The front levers M and their connected front levers R', are then similarly 25 acted upon to operate the folder plates 29 and 30, to turn the remaining edges of the blanks; the relative difference in length of the recesses 6 and 9, allowing the rearward levers R and their connected parts to operate before the forward levers R'. Further movement of the piston D, operates the 30 rocking levers 1, to carry the bed B, upwardly to heat and press the blanks, through the medium of the yoke H and the rods J, the rollers 3, directly carrying the bed B, upwardly.

35 The retarding action of the oil in the cylinder F, prevents abrupt and jarring movement of the cylinder, whereby all operating parts move smoothly.

40 The rotatably adjustable bushings and their slides admit of accurate and variable adjustment of the folder plates for differential and independent movement required for folding blanks of various shapes, and the simplicity of construction of the various 45 parts and their automatic movements provide a machine of the character described which is very effective and economical of operation.

45 It is especially noteworthy that the adjustable stops y, which are threaded to each rod U, admit of accurately gaging the downward movement, or stroke of the said rods, thus permitting a wide range of adjustment and slidable movement for different shaped folder-plates and dies; and the 50 knobbed presser fingers, being removable with the slides and folders admits of their being removed and kept in proper relative arrangement when it is desired to replace 55 them with a new set.

Having thus described my invention, what I claim as new, and desire to secure by Letters Patent, is:—

60 1. In a folding machine comprising a frame-work, folders, a reciprocating cross-head and die, and a spring-supported reciprocating heated bed, the combination of reciprocating rods having angularly extended parts, slides engaging said parts, and means 65 connecting said folders with said slides, and

lever means for operating said rods, cross head and bed, and an actuating means comprising a reciprocating piston having a recessed cam faced piston rod, the recesses of said rod adapted for operating said lever 70 means.

2. In a folding machine comprising an upwardly and downwardly movable cross-head and die, a reciprocating spring-supported bed adapted to be heated, folder 75 plates, and slides for operating them, and rods each having an angularly extended part for engaging said slides, and lever means for operating said parts, the combination of a power-operated reciprocating piston, a valve device, a cam faced piston rod, and a pedal bar.

3. In a folding machine the combination, of a reciprocating spring-supported bed adapted to be heated, folders, and rods having angularly extended parts for operating said folders, and slides for connection with said folders, and a reciprocating head and die, and swinging means supporting said head and die, and lever means for operating said parts and a treadle bar and treadle; with a power-operated reciprocating piston and cylinder therefor, a piston-rod having two cam faces each having a vertical and a 85 beveled face, said piston rod having an extension, and a piston connected to said extension, and an oil-containing cylinder therefor having an adjustable bypass for retarding the oil flow, said recessed piston rod operating said lever means.

4. In a folding machine the combination of a frame-work, folders, a reciprocating cross head and die, and a spring-supported reciprocating heated bed, with reciprocating and turnably adjustable rods having angularly extended parts, turnably adjustable slides engaging said parts, said slides connected with said folders, and means connecting said folders and slides whereby said folders move back and forth, and lever means for operating said rods, cross head and bed, with an actuating means comprising a reciprocating piston having a piston rod mounting cam faces, the cam faces of said rod adapted for operating said lever 100 means.

5. In a folding machine of the class described, the combination, of a reciprocating head and die, folders for turning the edges of a blank over said die, a reciprocating heated bed, lever means for operating said parts, and a presser for operating said die head comprising swinging curved arms mounted upon a common shaft and yieldably connected by a spring, one of said arms having a shoe, for engaging said lever means; with an actuating means comprising a reciprocating piston and cam faced piston rod, said cam faced rod adapted for operating said lever means.

6. In a hanger for a head and die for folding machines, the combination of a curved presser arm having extensions for connection with the die head, and a curved arm having a shoe, and a yieldable connection between said arms, comprising a set screw and spring, said arms mounted and swinging on a common shaft.

7. In a means for operating folders of a folding machine, the combination with a slide and means mounting said slide, said slide having an angularly extended opening therethrough, of a reciprocating rod having an angularly extended part engaging said opening means for rotating said slide relative to said rod to adjust its stroke, said slide engaging a folder and driving the same back and forth.

8. In a means for operating folders of a folding machine the combination, with a turnably adjustable slide and means for mounting said slide, said slide having an angularly extended opening therethrough, of a reciprocating rod having an angularly extended part engaging said opening, means for rotating said slide relative to said rod to adjust its stroke and adjustable means on said rod for gaging its thrust, said slide engaging a folder and moving said folder back and forth.

9. In a hanger for a head and die for folding machines, the combination, of a presser arm for connecting with the die head, and an arm extending forwardly over and rearwardly away from said presser arm, said last named arm having a shoe at its free end; with a yieldable means connecting said arms; and pivot means for supporting said arms, whereby swinging motion may be jointly imparted thereto, said yieldable means admitting of slight independent movements of said arm.

10. In a means for operating a head and die for folding machines, the combination, of a presser arm for connection with the die head, and an operating arm extending forwardly over and rearwardly away from said presser arm, said last named arm having a shoe at its free end, and a yieldable means connecting said arms, and a lever, and means on said operating arm for adjustably controlling the swing of said lever, and a depending connecting-rod in pivotal connection with the free end of said lever, said rod adapted for connection with means for operating it, said shoe on said operating arm adapted for contact with lever-means for controlling the movement of said arm.

11. In a folding machine comprising a frame-work, folders, a reciprocating cross head and die, and a spring supported reciprocating bed; the combination, of reciprocating rods having angularly extended parts, slides engaging said parts, and means connecting said folders with said slides, and le-

ver means for operating said rods and bed, and an actuating means comprising a cylinder, valve device and connecting-rods, and a reciprocating piston rod having cam faced portions for actuating said lever means; with a means for hanging and operating said head and die comprising a presser arm connected to the die head, and an operating arm extended forwardly over and rearwardly away from said presser arm, and a shoe on the free end of said operating arm, and a yieldable means connecting said arms, and a lever, and means on said operating arm for adjustably controlling the swing of said lever, and a depending connecting rod pivoted to the free end of said lever, said lever, operating and hanging means pivoted on a common support; and pedal-operated.

12. In a machine of the class described, the combination, with a bed-plate for holding blanks to be folded and pressed, and supporting springs therefor, said springs mounted on levers, said levers having roller bearings; of piston means for operating said levers to impart reciprocating motion to said bed-plate.

13. In a machine of the class described, the combination, with a bed-plate for holding blanks to be folded and pressed, and supporting plate-springs therefor, and swinging levers having roller bearings, said levers carrying said springs, set-screws for adjusting said bed-plate, and piston means for operating said levers.

14. In a folding machine of the character described, a table having a well, a bed plate in said well, a die above said bed plate, means for supporting said die for movement towards and away from said bed plate, means for imparting movement to said supporting means, turning plates for folding the edge portions of a blank over the die, and an actuating means for said turning plates, including plungers movable vertically arms carried by said plungers, blocks movable horizontally by said arms, bars connected with said blocks and said turning plates for imparting movement to the latter when the plungers are moved, and means for moving said plungers.

15. In a machine as characterized, a plurality of converging folding sections; power-driven means for moving said sections, said means embodying a plurality of guided sliding heads; and transmission means connecting said heads and said folding sections; and means for changing the angle of movement of said heads.

16. In a machine as characterized, a plurality of converging folding sections; power-driven means for moving said sections, said means embodying a plurality of guided sliding heads; transmission means connecting said heads and said folding sections; and means for changing the angle of movement

of said heads, said means embodying a rotatable turret having an inclined perforation therethrough and a reciprocating member terminating in an inclined pin mounted in said perforation and inclined in correspondence therewith, said pin and perforation being so arranged that pressure applied

vertically on said pin results in a cam-like action on said head to move the same in the predetermined path thereof.

Signed at Cohoes in the county of Albany and State of New York this third day of

March A. D. 1922.

EDWARD B. ROBY.
